UNITED STATES PATENT OFFICE.

PETER E. MALMSTRÖM, OF BROOKLYN, NEW YORK.

SPRING-ROLLER FOR CURTAINS.

SPECIFICATION forming part of Letters Patent No. 324,135, dated August 11, 1885.

Application filed August 14, 1884. (No model.)

To all whom it may concern:

Be it known that I, PETER E. MALMSTRÖM, a citizen of the United States, residing at Brooklyn, (Greenpoint,) in the county of Kings and State of New York, have invented new and useful Improvements in Spring-Rollers for Curtains, of which the following is a specification.

This invention relates to a fixture for shade-rollers, which is composed of a casing, a stationary axle extending through the casing, a drum which revolves freely on this axle, a convolute spring, one end of which is secured to the stationary axle, while its other end is fastened to the interior of the drum, a revolving shaft which has its bearings in the heads of the casing, a square, polygonal, or oval stem extending from said shaft through the casing, a take-up roller the diameter of which is smaller than that of the drum, and which is made integral with or mounted firmly on this shaft, a tape or flexible strip of sheet metal, which extends several times round the drum, and has one end fastened to the circumference of the drum and its other end to the take-up roller, one or more notches formed in the take-up roller, and a click mounted in such a position that it bears upon the circumference of said roller, so that when the square stem is introduced into a corresponding socket in the end of a shade-roller and the shade is pulled down, the spring is slowly wound up and retained in this position by the click, provided the movement of the shade is slow; but if the shade is moved fast the click is released, so as to permit the shade to rewind on its roller by the action of the convolute spring, the principal advantage of my fixture being based upon the difference in the diameter of the take-up roller and of the drum, which is of such a nature that four or more revolutions of the take-up roller are required to produce one revolution of the drum, and consequently the tension of the spring undergoes a comparatively slight change when the shade is drawn down.

In the accompanying drawings, Figure 1 represents a vertical section of my fixture in the plane $x x$, Fig. 3. Fig. 2 is a face view of the same. Fig. 3 is a transverse section of the same in the plane $y y$, Fig. 1. Fig. 4 is a sectional end view of the shade-roller, the plane of section being indicated by the line $z z$, Fig. 3.

Similar letters indicate corresponding parts. In the drawings, the letter A designates the casing, which is made of brass or any other suitable material, and which is so constructed that it can be readily put up in the required position. In this case is firmly mounted an axle, B, on which turns a drum, C, which contains the convolute spring D, one end of this spring being secured to the axle and the other to the drum. On the circumference of the drum is firmly secured one end of a tape or flexible strip of sheet metal, E, which is wound round the drum several times, and the other end of which is fastened to a roller, F, which is firmly mounted on or made integral with a rotary shaft, G. This shaft has its bearings in the heads of the casing A, and it is provided with an extension, H, the cross-section of which is square, polygonal, or oval. In the interior of the casing is situated a click, I, which swings loosely on its pivot a , and which bears upon the circumference of the roller by its own gravity, if the casing is put up in its working position, so that it drops in gear with one or more notches, $b b$, formed in one end of the roller, provided the shaft is revolved slowly. The extension H of the shaft G fits into a socket, c , in a metallic plate, J, which is fastened to one end of the shade-roller K. The diameter of the roller F is considerably smaller than that of the drum, so that if the shade, which is secured on the roller K, is drawn down, the drum C makes only one revolution for every four (or more) revolutions of the shaft G, and consequently the tension of the spring D undergoes comparatively little change by the operation of the shade, and it is not liable to get out of order for a long time.

What I claim as new, and desire to secure by Letters Patent is—

A fixture for shade-rollers composed of a casing, a stationary axle fixed in said casing, a drum which revolves freely on this axle, a convolute spring, one end of which is secured to the stationary axle, while its other end is fastened to the interior of the drum, a revolving shaft which has its bearings in the heads of the casing, a square, polygonal, or oval stem extending from said shaft through the casing, a take-up roller the diameter of which is smaller than that of the drum, and which is

made integral with or mounted firmly on the shaft, a tape or flexible strip of sheet metal extending several times round the drum, and having one end fastened thereto, while its other end is fastened to the take-up roller, one or more notches formed in the take-up roller, and a click which bears upon the circumference of the take-up roller, all constructed substantially as and for the purpose shown and described.

In testimony whereof I have hereunto set my hand and seal in the presence of two subscribing witnesses.
